[57] CLAIM

The ornamental design for a diver's tool, as substantially shown.

DESCRIPTION

FIG. 1 shows a perspective view of my new and ornamental design for a diver's tool;
FIG. 2 shows a side elevation view of my invention in the same direction as seen in the perspective view of FIG. 1;
FIG. 3 shows a bottom view looking upwardly at the perspective view of FIG. 1;
FIG. 4 shows a side elevation view on the opposite side from that shown in the perspective view of FIG. 1;
FIG. 5 shows an end view of my design for a diver's tool in the direction of lines 5—5 of FIG. 2; and,
FIG. 6 shows an end view in the opposite direction from that of FIG. 5.
